UNITED STATES PATENT OFFICE.

JOHN LEHNER, OF PITTSBURGH, PENNSYLVANIA.

SUCTION MECHANISM FOR DENTAL PLATES.

1,255,027.

Specification of Letters Patent. Patented Jan. 29, 1918.

Application filed March 21, 1917. Serial No. 156,477.

To all whom it may concern:

Be it known that I, JOHN LEHNER, a citizen of the United States, and residing in the city of Pittsburgh, in the county of Allegheny and State of Pennsylvania, have invented or discovered new and useful Improvements in Suction Mechanism for Dental Plates, of which the following is a specification.

10 My invention comprises new and useful improvements in suction devices for upper dental plates whereby said plates are held in place against the wearers' palates.

The difficulty in the forms of suction devices now in general use for that purpose is that they occupy so much space that the plate is spaced away from the palate and thus lacks proper support against oscillation or wabbling.

20 In the use of my improved suction devices the plate is held snugly and solidly against the palate over its entire area, so that the teeth are always held solidly in proper position and their chewing action is 25 natural and causes no discomfort to the wearer.

More particularly, my invention consists in fixing a pair of relatively small soft rubber cups in apertures extending through the 30 dental plate at either side of the medial line of the latter, the open, top edges of the cups protruding slightly above the surface of the dental plate so as to obtain a suction hold on the palate without spacing the plate 35 away from the palate.

In the accompanying drawings, Figure 1 is a top plan view of an upper dental plate embodying my invention; Fig. 2 is a bottom plan view of the same; Fig. 3 is a sectional view along the line III—III in Fig. 1; Fig. 4 is a perspective of one of the suction cups before it is mounted in the plate, and Fig. 5 is a side view of the same.

The following is a detailed description of 45 the drawings.

A represents an upper dental plate whose top surface is molded in the usual manner to fit snugly against the wearer's palate. On either side of the medial line, *a*—*b* in 50 Fig. 1, of the plate, I provide an aperture 1 extending through the plate and preferably elongated from front to rear of the plate, as shown. These apertures are formed by inserting in the plate before vulcanization of 55 the rubber small plates of air-chamber metal of the proper thickness and edge contour to

form said apertures with a knife slot 2 running around their walls, as shown. When the plate has been vulcanized, the plate of air-chamber metal is cut and drawn out of 60 the aperture, leaving the same in proper form to receive the suction cups.

In each of said apertures 1 is inserted upwardly a soft rubber cup B, having its open top turned upwardly, and provided 65 with a circumferential flange or lip 3 integral with its side wall and seating in the slot 2.

Suitable cement is used to fix the cups in place.

The soft rubber upper edge of the cup 70 extends sufficiently above the top surface of the plate to obtain a suction grip on the palate without spacing the plate away from the palate. This protrusion should not be 75 more than, say, a thirty-second of an inch. The bottom of the cup is rounded and smooth and protrudes slightly below the bottom surface of the plate.

When the plate is inserted into the 80 mouth, the tongue is pressed lightly against the bottoms of the cups, thus contracting the latter somewhat, so that when the plate is pressed snugly into contact with the palate, and the tongue dropped, suction action will 85 at once ensue which will hold the plate snugly in contact with the palate without danger of oscillation or wabbling. Thus the teeth will be properly and positively supported in proper position and the action of 90 chewing will be natural and without discomfort or abrasion to the membrane of the roof of the mouth.

By elongating the apertures, and consequently the cups from front to rear of the 95 plate, a better gripping action is obtained and a more uniform contact between the plate and the palate.

When a cup becomes worn out or punctured, it may be torn from its aperture and 100 a new one cemented into place at very slight expense, and with a very temporary loss of use of the plate.

My invention may be applied to dental plates with much less expense than can any 105 other suction devices now in general use, and its use results in great comfort to the wearer and satisfactory anchoring of the plate in the mouth.

What I desire to claim is:

1. The combination of a dental plate of 110 hard material, apertures extending com-

pletely through the palatable portion of the plate, a rubber suction trough positioned in each aperture having its closed portion protruding slightly below the lower surface of the plate and its free continuous edge protruding slightly above said plate and means for holding said cup within the aperture.

2. The combination of a dental plate of hard material, apertures extending completely through the palatable portion of the plate, a rubber suction trough positioned in each aperture having its closed portion protruding slightly below the lower surface of the plate and its free continuous edge pro-

truding slightly above said plate and a tongue and groove engagement between the trough and the wall of the aperture for holding the said trough within the aperture.

3. As an article of manufacture, a suction cup for dental plates having an open top, a closed bottom and an encircling rib for securing the cup in position within the dental plate.

Signed at Pittsburgh, Penna., this 19th day of March, 1917.

JOHN LEHNER.
